DESIGN FOR AN I-BEAM CLAMP

William T. Graham, Amarillo, Tex.

Application June 14, 1946, Serial No. 130,724

Term of patent 14 years

(Cl. D54—2)

To all whom it may concern:

Be it known that I, William T. Graham, a citizen of the United States, residing at Amarillo, in the county of Potter and State of Texas, have invented a new, original, and ornamental Design for an I-Beam Clamp, of which the following is a specification, reference being had to the accompanying drawing, forming a part thereof.

In the accompanying drawing, which forms a part of the instant specification and is to be read in conjunction therewith,

Fig. 1 is an end elevational view of an I-beam clamp, showing my new design;

Fig. 2 is a view taken along the line 2—2 in Fig. 1, in the direction of the arrows;

Fig. 3 is a view taken along the line 3—3 in Fig. 1, in the direction of the arrows; and

Fig. 4 is a view taken along the line 4—4 in Fig. 1, in the direction of the arrows.

Having described the invention, what is claimed is:

The ornamental design for an I-beam clamp, substantially as shown.

WILLIAM T. GRAHAM.
